(57) **CLAIM**

The ornamental design for a microphone noise reducer, as shown and described.

DESCRIPTION

FIG. 1 is a top perspective view of a microphone noise reducer.

FIG. 2 is a bottom perspective view of the microphone noise reducer as shown in FIG. 1.

FIG. 3 is a front view of the microphone noise reducer as shown in FIG. 1.

FIG. 4 is a back view of the microphone noise reducer as shown in FIG. 1.

FIG. 5 is a right side view of the microphone noise reducer as shown in FIG. 1, the left side view being a mirror image of the right side view.

FIG. 6 is a top view of the microphone noise reducer as shown in FIG. 1; and,

FIG. 7 is a bottom view of the microphone noise reducer as shown in FIG. 1.

1 Claim, 7 Drawing Sheets
